UNITED STATES PATENT OFFICE.

GEORGE W. BAYLEY, OF NEW YORK, N. Y., ASSIGNOR TO BAYLEY & SONS, INC., OF BROOKLYN, NEW YORK, A CORPORATION OF NEW YORK.

ELECTRIC-LIGHTING FIXTURE

1,156,454.

Specification of Letters Patent.

Patented Oct. 12, 1915.

Application filed June 4, 1915. Serial No. 32,216.

To all whom it may concern:

Be it known that I, GEORGE W. BAYLEY, a citizen of the United States, resident of the borough of Brooklyn, county of Kings, city and State of New York, have invented a certain new and useful Improvement in Electric-Lighting Fixtures, of which the following is a specification.

This invention relates to improvements in electric lighting devices.

One of the objects of the invention is to secure the greatest electric light efficiency without distressing effects to the eyes of the user.

Another object is to produce a device which will be of pleasing appearance and in which the parts may be readily separated for the purpose of cleaning.

These and further objects will more fully appear from the following specification and accompanying drawings, considered together or separately.

In the drawings, Figure 1 is a top view of a device embodying my invention; Fig. 2 is a sectional view on the line 2, 2 of Fig. 1; Fig. 3 is an enlarged view of a portion of the shade showing the bottom binding channel thereof, such section being taken through one of the ribs; Fig. 4 is a view of a similar part, but taken through a panel; Fig. 5 is a sectional view on the line 5, 5 of Fig. 3; Fig. 6 is a sectional view on the line 6, 6 of Fig. 4; Fig. 7 is an enlarged view, in section, of the upper part of the shade showing the collar; Fig. 8 is a sectional view on the line 8, 8 of Fig. 7; and Fig. 9 is a sectional view on the line 9, 9 of Fig. 8.

In all of the views like parts are designated by the same reference characters.

The device comprises a shade 1 and a dish 2. These two parts are assembled so that the lamp 3 is substantially inclosed by both shade and dish. The lamp is supported upon the usual socket 4 having a supporting eye 5. Associated with this eye is the usual canopy 6.

The shade is formed of a plurality of panels 7 made of glass, preferably of a translucent character. These panels are secured together by ribs 8. These ribs, best shown in Figs. 5 and 9, have a center web and two flanges forming an H shape cross-section. The ribs are best made of metal.

These ribs are secured together by a top binding channel 9 and a bottom binding channel 10. The width of the top and bottom binding channels is the same as the thickness of the panels. The shape of the two binding channels 9 and 10 is that of a flat ring with its walls inclined to accommodate the inclination of the panels at the edges thereof, leaving the rings respectively vertical and horizontal. The flanges on the ribs are cut away adjacent to the two channels and the web part only of the ribs enters the channels. This is shown in Figs. 3, 7 and 8. Where the webs enter the channels they are secured to the channels by solder or other fastening means. A neck 70 collar 11 is secured to the top binding channel by solder or other means.

The dish 2 is formed preferably of glass of a translucent character with its outer edge covered by a binding channel 12 preferably of metal. The dish is secured to the shade by means of eyes 13 attached to the inner sides of the ribs at suitable points. In each eye is a link 14. The binding channel 12 of the dish is provided with hooks 80 15 which engage with the links. The canopy 6 may be secured to the collar 11 by any suitable means, such as screws 16.

In the following claims I employ the term "glass" as defining the material out of which the shade and dish are made, but it is to be understood that this is a generic term chosen to cover substances besides glass, such as porcelain, which will not fully obstruct the passage of the light.

In accordance with the provisions of the patent statutes, I have described the principle of my invention, together with the apparatus which I now consider to represent the best embodiment thereof; but I desire to have it understood that the apparatus shown is merely illustrative and that the invention may be carried out in other ways.

Having now described my invention, what I claim as new and desire to secure by Letters Patent, is:

1. An electric lighting fixture having a shade and dish, the shade being formed of a plurality of panels formed of glass, said panels being secured together by ribs, top binding channels and bottom binding channels, each of the shape of a flat ring with inclined walls to accommodate the inclina-

tion of the panels at the edges thereof, means for securing the ribs to the channels, and means for connecting the dish to the shade.

2. An electric lighting fixture having a shade and dish, the shade being formed of a plurality of panels formed of glass, said panels being secured together by ribs of H-shaped cross-section, top binding channels and bottom binding channels, each of the 10 shape of a flat ring with inclined walls to accommodate the inclination of the panels at the edges thereof, the flanges on the ribs being cut away adjacent to the two channels and the web part of the ribs entering the 15 channels and secured thereto, and means for connecting the dish to the shade.

3. An electric lighting fixture having a shade and dish, the shade being formed of a plurality of panels formed of glass, said 20 panels being secured together by ribs, top binding channels and bottom binding channels, each of the shape of a flat ring with inclined walls to accommodate the inclination of the panels at the edges thereof, the dish being formed of glass with a binding channel on the edge, hooks carried by the 25 said channel, eyes carried by the ribs of the shade and links carried by the eyes and engaging with the hooks, a collar connected to the top 30 binding channel of the shade, a canopy engaging with the collar, and a lamp socket carried by the canopy.

4. An electric lighting fixture having a shade and dish, the shade being formed of a plurality of panels formed of glass, said 25 panels being secured together by ribs of H-shaped cross section, top binding channels and bottom binding channels, each of the

shape of a flat ring with inclined walls to accommodate the inclination of the panels at the edges thereof, the flanges on the ribs being cut away adjacent to the two channels and the web part of the ribs entering the channels and secured thereto, the dish being formed of glass with a binding channel on 45 the edge, hooks carried by the said channel, eyes carried by the ribs of the shade, and links carried by the eyes and engaging with the hooks.

5. An electric lighting fixture having a shade and dish, the shade being formed of a plurality of panels formed of glass, said panels being secured together by ribs of H-shaped cross-section, top binding channels and bottom binding channels, each of the 50 shape of a flat ring with inclined walls to accommodate the inclination of the panels at the edges thereof, the flanges on the ribs being cut away adjacent to the two channels and the web part of the ribs entering the 55 channels and secured thereto, the dish being formed of glass with a binding channel on the edge, hooks carried by the said channel, eyes carried by the ribs of the shade and links carried by the eyes and engaging with the hooks, a collar connected to the top 60 binding channel of the shade, a canopy engaging with the collar, and a lamp socket carried by the canopy.

This specification signed and witnessed 70
this 27th day of May, 1915.

GEORGE W. BAYLEY.
